UNITED STATES PATENT OFFICE.

HENRY SPENCER BLACKMORE, OF MOUNT VERNON, NEW YORK.

PROCESS OF MAKING CYANIDS.

No. 889,097.

Specification of Letters Patent.

Patented May 26, 1908.

Application filed December 13, 1902. Serial No. 135,074.

To all whom it may concern:

Be it known that I, HENRY SPENCER BLACKMORE, a citizen of the United States, residing at Mount Vernon, in the county of Westchester and State of New York, have invented certain new and useful Improvements in Processes of Making Cyanids; and I do hereby declare the following to be a full, clear, and exact description of the invention, such as will enable others skilled in the art to which it appertains to make and use the same.

The object of my invention is to make cyanids, such as potassium or sodium cyanids, and consists in deoxidizing, in the presence of nitrogen or a nitrogen-yielding compound, a heated, molten or liquefied oxy-salt or compound of a metal, the cyanid of which is desired, by the action of an endothermic carbid, the electro-positive element of which has greater affinity for the oxygen content of the oxy-salt or compound employed, thereby liberating nascent carbon and the metal, a cyanid of which is desired, simultaneously with or in the presence of nitrogen whereby a union of the said elements is achieved.

My invention is particularly adaptable to the fixation of free nitrogen, such as may be obtained from the atmosphere, with carbon in the presence of an alkali, whereby the formation of cyanids may be readily accomplished directly in a practical and economical manner yielding a product uncontaminated with injurious foreign ingredients, and is based upon the discovery that oxy-salts or compounds of a metal, the cyanid of which is desired, may, in a heated condition, in the presence of nitrogen, be deoxidized by the electro-positive element or base of a carbid, thereby generating nascent carbon and the metal of the compound employed, which nascent carbon and metal simultaneously unite with the nitrogen present, producing cyanid.

My invention is also based upon the discovery that by employing carbids of endothermic nature, such as acetylene, which evolve heat during their transformation, the formation of cyanids in the presence of nitrogen is greatly facilitated, the reaction governed and controlled in a more perfect manner, and a larger yield attained with less danger of contamination of the product with foreign ingredients than has resulted hitherto.

As an example of the manner in which my process can be carried out on a practical

basis I will take, for example, the production of potassium and sodium cyanids from their corresponding hydrates or hydroxids, reference being had to the accompanying drawing which illustrates an apparatus which I have devised for carrying out the same, Figure 1 of which represents a transverse vertical section of the apparatus, and Fig. 2 a vertical longitudinal section showing the conversion pots or receptacles connected in multiple.

In carrying out my invention on a practical basis I prefer to introduce into the conversion pot or receptacle A, which is lined with a material B such as magnesite not acted upon by the materials employed or the product produced, through the opening D in the cover or closure E, a mixture of potassium and sodium hydroxids in proportion of one of the former to two of the latter by weight and proceed to fuse the same or reduce it to a molten condition by means of heat generated in the furnace C by any suitable means. I find that the mixture of hydroxids aforementioned, viz., potassium hydroxid and sodium hydroxid fuses at a lower temperature than either *per se*, approximately 300 degrees C., and conversion into cyanid is also more readily effected.

When the mixture has assumed a molten, liquefied or free circulating condition approximately 300° C., I close the opening D by means of the cover e, and then introduce into and through the molten compounds, through the pipe F, controlled by the valve G, a mixture of nitrogen which has been preferably superheated to approximately 260° C., and an endothermic hydrogen carbid, such as acetylene, the lower end of the pipe F which extends into the molten compounds in the conversion pot or receptacle A, being composed of a material which is not acted upon by the ingredients employed or the products produced, such as magnesite, and the said section being united to the pipe F by means of the union h.

As the mixture of superheated nitrogen and endothermic hydrogen carbid, such as acetylene, is introduced into and through the molten or liquefied potassium and sodium hydroxids the hydrogen of the acetylene combines with the oxygen of the hydroxid concurrently releasing an alkali-metal and carbon which in their nascent condition in the presence of the nitrogen immediately unite forming an alkali cyanid, the oxygen of the compound which has thus combined with

the hydrogen, passing off at the temperature employed in the form of steam, the heat which is liberated by the decomposition of the endothermic acetylene within the body 5 of the reacting ingredients assisting in maintaining the same at a reacting and uniting temperature thereby rendering the application of external heat of secondary consideration and effecting a saving in the wear and tear of apparatus as well as fuel which would otherwise be consumed to maintain ingredients at the required reacting temperature; any excess of heat accumulating in the mass during reaction is removed by the refrigerating 10 action of the gases evolved and also by an excess of acetylene or other gases introduced into or passing through and out of the apparatus, it being noted that the excess of acetylene over that required for reaction is 15 practically inert with reference to the process except as a refrigerating or heat absorbing and conveying agent.

The reaction which takes place may be illustrated by the following chemical formula 25 or equation:

or employing alkali oxids instead of hydroxids, as follows:

As the process of conversion progresses 35 more alkali-hydroxid may be added from time to time through the opening D whereupon it assumes a molten or liquefied condition by becoming dissolved in or liquefied by the cyanids previously produced, and therefore 40 fore it can be readily seen that I may convert the oxy-compounds into cyanids either in a molten condition *per se* or liquefied by the action of inert chemical salts by exposing the said molten or liquefied oxy-compounds to 45 the action of an endothermic carbid, the electro-positive element or base of which is capable of uniting with the oxygen of the oxy-salt or compound concurrently liberating carbon and the metal, a cyanid of which is 50 desired, in the presence of nitrogen.

It is obvious that the temperature of the reacting ingredients must be maintained, by refrigeration or otherwise, below the temperature at which the base or electropositive 55 element of the endothermic carbid has the superior affinity for oxygen combined in the compound of metal, a cyanid of which is desired, over carbon, which in the case of acetylene is approximately 327° C., the same being 60 about the limit at which hydrogen thereof has a superior affinity for the oxygen combined in a mixture of caustic soda and caustic potash, while employing such endothermic hydrocarbons, over its carbon contents.

65 I do not desire to confine myself to the em-

ployment of endothermic hydrogen carbids as reducing agents in the formation of cyanid but reserve the right to employ any other practical metallic carbid of endothermic nature which may be adaptable for the purpose, *i. e.*, the electro-positive element of which is capable of abstracting the oxygen from the oxy-salt or compound of the metal, a cyanid of which is desired, it being a well known and established fact that hydrogen 70 is a metal in a gaseous state or condition at ordinary atmospheric pressure and temperature from a chemical standpoint just the same as the metal mercury exists as a liquid under like conditions. When an endothermic metal carbid, other than hydrogen carbid is employed, it is preferably introduced into the oxygen-containing alkali-metal compound in a fine state of division suspended in the nitrogen-bearing fluid. I 75 can also employ any other oxy-compound of the metal, a cyanid of which is desired, either in a molten condition *per se* or dissolved, liquefied, or retained in a molten bath 80 of inert chemical compounds. When the 85 oxy-compound in the conversion pot or receptacle A has been converted into cyanid it may be withdrawn from time to time as desired through the tap-hole H by withdrawing the plug or stopper J by means of 90 the actuation of the screw-threaded closing device K.

I find it of advantage both from economical and practical standpoints to add alkali carbonates from time to time to the molten 100 constituents of the conversion pot or receptacle whereby in its liquefied condition in the inert contents of the said receptacle it is as readily converted as the more fusible alkali oxy-compound. I can also introduce the 105 nitrogen in the form of a hydrid or other nitrogen-yielding compound instead of free nitrogen together with the endothermic hydrogen carbid by which means nitrogen and carbon are both liberated concurrently with the alkali metal by the union of the hydrogen combined with both the nitrogen and carbon with the oxygen of the alkali metal compound, or I can employ any compound capable of producing or releasing free or nascent 110 nitrogen in a form capable of uniting with a nascent metal and carbon to form a cyanid. I also intend to include as my invention the heating of the ingredients, *viz.*, metallic oxy-salts or compounds, carbid of 115 the character described and nitrogen, to a reacting temperature which may, in some cases, not actually be a molten or liquefied condition at the time of reaction but which later may become molten or liquefied by action of the more fusible cyanid produced.

The compounds herein referred to, designated by the prefix "oxy" to metallic salts or compounds employed for transformation, is intended to include all salts or compounds 120

to metal or metals, cyanid of which is desired, containing oxygen either individually or associated with other non-metallic elements and the term "metallic carbid" to 5 an endothermic compound of solid, liquid or gaseous metal with carbon, be it either a normal carbid, acetylid or other union and is intended to include any mixture or combination of carbids as well as a simple carbid 10 *per se*, the electro-positive element or base of which is capable of abstracting the oxygen from the oxy-salt or compound of the metal, 15 a cyanid of which is desired. I can also perform the conversion into cyanids of the oxy-salts or compounds of the metal or metals, a cyanid of which is desired, by employing inert salts or compounds which may facilitate 20 fusion by dissolving or suspending the same in a state of fusion whereby the transformation into cyanid is also facilitated; and I can expose the compounds to be transformed to a heat capable of fusing it and introduce the nitrogen and carbid of the character described after fusion or during fusion or I can 25 add the same to the fused composition or expose the mixture of oxy-salt or compound, nitrogen and the endothermic carbid, to a reacting temperature without departing from the spirit of my invention which con- 30 sists in deoxidizing an oxy-salt or compound of the metal or metals, a cyanid of which is desired, by action of the electro-positive element or base of an endothermic carbid at a reacting temperature whereby the carbon and 35 metal, a cyanid of which is desired, thus concurrently released in the presence of nitrogen, unite therewith to form cyanid.

I am aware that processes have been devised for uniting nitrogen directly and 40 directly with carbids of metals, cyanids of which are desired, it being noted that the metal and carbon are united and the formation of cyanid depends on the absorption of the nitrogen, but in these cases the carbids 45 being fusible only at extremely high temperatures merely admit of superficial action thereby producing contaminated cyanids below fusion, and if heated to fusion preclude the formation of cyanids by being at a tem- 50 perature above the dissociating point of the cyanid, also in these cases noted, the metal, a cyanid of which is desired, is exposed to the action of nitrogen while it is combined with carbon in the form of a carbid, while in my 55 process I employ carbon in a free nascent condition in the presence of a nascent metal, a cyanid of which is desired, and nitrogen, which nascent condition greatly facilitates the perfect combination and fixation of 60 nitrogen.

The endothermic carbid which I prefer to employ in the formation of cyanids, viz., hydrogen carbids (acetylene) are those which are not affected or decomposed by the 65 action of moisture at ordinary temperatures

and the electro-positive element or base of which is capable of abstracting oxygen from the oxy-salts or compounds of the metal, a cyanid of which is desired, with the simultaneous release of the carbon of the carbid, which released elements unite with the nitrogen present forming cyanid. It is also preferable to employ an excess of acetylene circulating through the molten alkali with the nitrogen so that the water vapor (H_2O) 70 liberated during deoxidation of the alkali (KOH—NaOH) with the hydrogen content of the acetylene is rapidly carried out and away from the cyanid to prevent the formation of ammonia and consequent loss of 75 cyanid, also the excess of heat of reaction is thereby removed thus regulating and maintaining the temperature at a point at which the electro-positive element of the carbid has an affinity for the oxygen of the oxy-compound employed to the exclusion of or preference to carbon, the excess of acetylene over that entering into reaction being inert, naturally acts merely as an absorber and conveyer of the heat from the reacting ingredients, which regulation and maintenance of temperature is governed by the quantity of inert gaseous body employed with relation to the heat generated in the reaction.

By employing molten alkali containing 95 iron oxid, alkali ferrite, or similar iron compound, alkali ferro-cyanid can be produced. I can also introduce the nitrogen into and through the oxy-salt of the metal, a cyanid of which is desired, in combination with carbon and hydrogen, such as pyridin (C_5H_5N) in a fluid condition instead of nitrogen hydrid as aforementioned while the ingredients are heated to a reacting temperature, in which case the union of the hydrogen with the oxygen of the oxy-compound liberates carbon and nitrogen from the pyridin or similar nitro-hydrocarbon which nascent nitrogen and carbon unite directly with the nascent metal concurrently liberating forming a cyanid therewith. The spirit of my invention, therefore, consists in the reduction of a metal, the cyanid of which is desired, concurrently with the production of nascent carbon in the presence of nitrogen, either free, or liberated from fluid compounds containing nitrogen in the process, whereby the nascent metal, nascent carbon and nitrogen unite directly forming a cyanid, and I do not desire to confine myself to the employment of any particular or specific compound or compounds in producing the cyanid as set forth but reserve the right to employ any ingredients which may justly be considered to come within the scope of my 100 invention as broadly hereinbefore set forth.

In carrying out this process it is sometimes found, especially when the larger percentage of the oxy-salt or compound of the metal, a cyanid of which is desired, has been 105

converted into cyanid, that the heat causes a direct dissociation of a portion of the acetylene or endothermic carbid into particles of free carbon and hydrogen gas which particles of free carbon remain suspended in and disseminated throughout the molten cyanid thereby temporarily contaminating the same. After all the oxy-salt or compound has been transformed into cyanid I remove these contaminating particles of free carbon by passing into or through the molten mass a current of oxygen or ordinary air whereby a portion of the metallic cyanid becomes converted into cyanate which, in turn, is reduced to cyanid by combination of the oxygen thereof with the free particles of carbon, thereby forming and eliminating carbonic acid and leaving the cyanid in a pure and uncontaminated condition. Care must be taken, however, that an excess of oxygen is not introduced, otherwise more carbon or other de-oxidizing agent, such as hydrogen, would have to be supplied in order to finally remove the same and reduce it again to cyanid. I find it of advantage, however, to introduce into the molten cyanid containing suspended particles of carbon, the percentage of which has previously been ascertained, a quantity of cyanate containing oxygen enough in proportion to the free carbon content to remove the same in the form of carbonic acid, by which means the excess of either free carbon or oxygen in the form of cyanate is avoided and the direct formation of cyanate for the removal of the particles of carbon within the cyanid is dispensed with.

By employing carbids of endothermic nature, such as acetylene, for the purpose of producing nascent carbon and nascent metal by the combination of the base of the carbid with the oxygen content of the oxy-compound of the metal a cyanid of which is desired in the presence of nitrogen for the purpose of forming a cyanid, the heat evolved by the oxidation and disruption of the carbid both through oxidation and liberation of the occluded or retained heat from the endothermic carbid, naturally increases the temperature of the ingredients internally in a cumulative degree until a point is reached at which carbon has an affinity for the oxygen in preference to the base of the carbid, such as hydrogen in case acetylene is employed, thus retarding the process and rendering it inoperative from a practical standpoint. I have discovered, however, that if the temperature of the reacting ingredients which would thus become inoperative by reason of the accumulating heat and consequent elevated temperature through internal reaction is subjected to refrigeration whereby the temperature is maintained below the point at which carbon has a superior affinity for the oxygen over the base of the carbid employed, that the process can be carried on contin-

uously without interruption, destruction of ingredients, loss of product by decomposition or disintegration of apparatus by reason of an otherwise elevated temperature.

It will be noted that one of the important features of my process consists in the regulation and maintenance of the temperature of the reacting ingredients at a point at which the electro-positive constituent of the reducing agent has an affinity for the oxygen of the oxy-compound of the metal, a cyanid of which is desired, employed, to the exclusion of or in preference to the carbon content of the reducing agent, which regulation and maintenance of temperature is accomplished by abstracting the excess of heat liberated by the reacting ingredients during the formation of cyanid by the refrigerating action of inert heat absorbing agents and thereby preventing the temperature from rising to a point at which the formation of cyanogen compounds is precluded or retarded and the formation of by-products which would have a tendency to decompose or transform the cyanid is obviated.

I do not desire to confine myself in relation to this step of my process to the employment of any particular or specific heat absorbing agent to refrigerate the reacting ingredients and maintain the temperature below the decomposing or dissociating point of the cyanid desired to be produced, but reserve the right to employ any available or convenient means of abstracting or regulating the heat which will refrigerate the ingredients without injuriously affecting the formation of the product desired. This refrigeration may be accomplished by bringing in contact with or direct introduction into or through the mass of reacting ingredients of an inert heat absorbing or conveying agent, or the heat may be abstracted from the ingredients by means of any other absorbing agent through the medium of an inert conductor of heat such as the walls of the conversion pot or receptacle having in contact with the outer surface a heat absorbing agent such as a circulating or cooling body or jacket of metal capable of melting at a temperature below the point at which it is desired to maintain and carry out the process, the heat absorbed in this molten metal being abstracted or removed and the cooler portions of metal returned in juxtaposition to the heat conveying medium or walls of the conversion pot or receptacle.

It is well known that the margin of temperature, within which the union of nitrogen and carbon is accomplished, is very narrow and hence the reasons of many failures in the continuous and complete formation of cyanogen compounds as attempted heretofore and I have discovered that the continuous and complete formation of cyanogen compounds may be accomplished without

interruption by maintaining the temperature within the margin at which the carbon and nitrogen unite, by refrigeration, and by which refrigeration the temperature is maintained below the dissociating point of the cyanogen compound desired.

The heat absorbing agent employed to regulate and maintain the temperature in the formation of cyanogen compounds as hereinbefore set forth may be itself refrigerated or cooled below the temperature of the surrounding atmosphere before being used, or, in case the agent should be at or above the temperature of the surrounding atmosphere, its refrigerating effect would be still available so long as its temperature is below that at which the formation of cyanogen compounds is precluded the only difference being that larger volumes of the heat absorbing agent must necessarily be employed in a given time to accomplish an equivalent of refrigeration. This refrigerating effect can also be accomplished by bringing contact with the mass of reacting ingredients from time to time inert solids of fusible nature which will abstract the heat from the reacting ingredients on assuming a melted or fluid condition.

The term "inert to cyanid" employed herein is intended to imply and does imply that the substance is not decomposed, transformed, or otherwise injuriously acted upon by the metal cyanid desired, nor is the cyanid which is desired decomposed, transformed, or otherwise injuriously acted upon by the oxygen-containing compound of the metal a cyanid of which is desired, whereby either or both of the essential constituents, viz. the oxygen-containing compound a cyanid of which is desired, the carbid transforming agent, or the metal cyanid desired, are destroyed or injured by association.

Having now described my invention, what I claim as new and desire to secure by Letters Patent is:—

1. The process of making cyanid which consists in exposing an oxy-compound of a metal inert to cyanid, the cyanid of which is desired, to the action of an endothermic carbid, maintained at a temperature at which the electro-positive element or base of the carbid is capable of uniting with the oxygen of the oxy-compound in preference to carbon, and nitrogen.

2. The process of making cyanid which consists in exposing an oxy-compound of a metal inert to cyanid, the cyanid of which is desired, to the action of an endothermic carbid of a more electro-positive metal, maintained at a temperature at which the said electro-positive metal has an affinity for the oxygen of the oxy-compound in preference to carbon, in the presence of nitrogen.

3. The process of making cyanid which consists in exposing a molten or liquefied oxy-

compound of a metal inert to cyanid, the cyanid of which is desired, to the action of an endothermic carbid, maintained at a temperature at which the electro-positive element or base of the carbid is capable of uniting with the oxygen of the oxy-compound in preference to carbon, and nitrogen.

4. The process of making cyanid which consists in exposing a molten material containing an oxy-compound of a metal inert to cyanid, the cyanid of which is desired, to the action of an endothermic carbid, maintained at a temperature at which the electro-positive element or base of the carbid is capable of uniting with the oxygen of the oxy-compound in preference to carbon, and nitrogen.

5. The process of making cyanid which consists in exposing a molten composition containing an oxy-compound of a metal or metals inert to cyanid, the cyanid of which is desired, to the action of a metallic carbid of endothermic nature, maintained at a temperature at which the electro-positive element or base of the carbid is capable of uniting with the oxygen of the oxy-compound in preference to carbon, and nitrogen.

6. The process of making cyanid which consists in exposing a molten or liquefied oxy-compound of a metal inert to cyanid, the cyanid of which is desired, to the action of a gaseous endothermic carbid and nitrogen.

7. The process of making cyanid which consists in exposing an oxy-compound of a metal inert to cyanid, the cyanid of which is desired, to the action of an endothermic hydrogen carbid, maintained at a temperature at which the hydrogen has an affinity for the oxygen of the oxy-compound in preference to carbon, and nitrogen.

8. The process of making cyanid which consists in deoxidizing by the action of endothermic electro-positive reducing agents maintained at a reacting temperature, in the presence of nascent carbon and nitrogen, an oxy-compound of a metal inert to cyanid, the cyanid of which is desired.

9. The process of making cyanid which consists in inducing a union between the oxygen of an oxy-compound of a metal inert to cyanid, a cyanid of which is desired and the electro-positive element or base of an endothermic carbid, by heating the substances to a reacting temperature in the presence of nitrogen.

10. The process of making cyanid which consists in deoxidizing by the action of the hydrogen of an endothermic hydrogen carbid, at a reacting temperature, in the presence of nascent carbon and nitrogen, an oxy-compound of a metal inert to cyanid, the cyanid of which is desired.

11. The process of making cyanid which consists in exposing a composition containing an oxy-compound of a metal inert to cyanid, the cyanid of which is desired, an

endothemic hydrocarbon and nitrogen, to a temperature at which hydrogen has an affinity for the oxygen of the oxy-compound in preference to carbon, whereby the metal, carbon and nitrogen contents of the composition are brought to a combining condition and caused to unite by the concurrent combination of the hydrogen of the hydrocarbon and oxygen of the oxy-compound in the reacting ingredients.

12. The process of making cyanid which consists in deoxidizing a hydroxid of a metal inert to cyanid, the cyanid of which is desired, by the action of the electro-positive element of an endothermic carbid, in the presence of nascent carbon and superheated nitrogen at a reacting temperature.

13. The process of making cyanid which consists in exposing a molten composition containing an oxy-compound of a metal inert to cyanid, the cyanid of which is desired, to the action of acetylene and nitrogen at a temperature at which the hydrogen has an affinity for the oxygen of the oxy-compound in preference to carbon.

14. The process of making alkali-metal cyanid which consists in exposing an oxy-compound of the alkali-metal inert to cyanid, a cyanid of which is desired, to the action of an endothermic hydrocarbon and nitrogen at a temperature at which the hydrogen has an affinity for the oxygen of the oxy-compound in preference to carbon.

15. The process of making alkali-metal cyanid which consists in exposing oxids of the alkali-metals to the action of an endothermic hydrogen carbid and nitrogen, at a temperature at which the hydrogen has an affinity for the oxygen of the oxy-compound in preference to carbon.

16. The process of making alkali-metal cyanid which consists in exposing a molten composition inert to cyanid containing an alkali-metal and oxygen to the action of an endothermic hydrogen carbid and nitrogen.

17. The process of making alkali-metal cyanid which consists in exposing a composition inert to cyanid containing an alkali-metal oxid to the action of acetylene and nitrogen at a reacting temperature.

18. The process of making alkali-metal cyanid which consists in exposing a hydroxid of the alkali-metal, a cyanid of which is desired, to the action of acetylene and nitrogen at a reacting temperature.

19. The process of producing potassium cyanid which consists in exposing a molten compound inert to cyanid containing potassium and oxygen to the action of an endothermic hydrogen carbid and nitrogen.

20. The process of making potassium cyanid which consists in fusing caustic potash and introducing into and through the same an endothermic hydrocarbon and nitrogen

while the materials are heated to a reacting temperature.

21. The process of making potassium cyanid which consists in exposing a molten composition inert to cyanid containing potassium-hydrogen oxid (hydroxid) to the action of acetylene and nitrogen at a reacting temperature.

22. The process of making cyanid which consists in exposing an oxy-compound of a metal inert to cyanid, the cyanid of which is desired, to the action of an endothermic compound, at a temperature at which the electro-positive element or base of the compound is capable of uniting with the oxygen of the oxy-compound, and nitrogen, and finally removing any particles of free carbon contained therein by introducing into the mass an agent capable of converting the cyanid into cyanate in sufficient proportion to remove the contaminating carbon.

23. The process of making cyanid which consists in exposing an oxy-compound of a metal inert to cyanid, the cyanid of which is desired, to the action of an endothermic carbid of a more electro-positive element, in the presence of nitrogen and removing any excess of carbon contained therein by the action of a metallic cyanate.

24. The process of making cyanid which consists in exposing an oxy-compound of a metal inert to cyanid, the cyanid of which is desired, to the action of an endothermic hydrocarbon and nitrogen at a reacting temperature, and removing any excess of carbon contained therein by the action of a metallic cyanate.

25. The process of making cyanid which consists in exposing an oxy-compound of a metal inert to cyanid, the cyanid of which is desired, to the action of acetylene and nitrogen at a reacting temperature, and removing any excess of carbon contained therein by introducing into the mass an agent capable of removing the carbon.

26. The process of making alkali-metal cyanid which consists in exposing an oxy-compound of an alkali-metal inert to cyanid, the cyanid of which is desired, to the action of acetylene and nitrogen at a reacting temperature, and removing any excess of carbon contained therein by introducing into the mass an agent capable of removing the carbon.

27. The process of making potassium cyanid which consists in exposing potassium hydroxid to the action of acetylene and nitrogen, at a reacting temperature, and removing any excess of carbon contained therein by introducing into the mass an agent capable of removing the carbon.

28. The process of making potassium cyanid which consists in exposing potassium hydroxid to the action of acetylene and nitrogen, at a reacting temperature, and re-

- moving any excess of carbon contained therein by the action of an oxidizing agent.
29. The process of making cyanid which consists in exposing an oxy-compound of a metal inert to cyanid, the cyanid of which is desired, to the action of a fluid endothermic carbid and nitrogen and maintaining the temperature at a point at which the electro-positive element of the carbid has an affinity for the oxygen of the oxy-compound in preference to carbon.
30. The process of making cyanid which consists in deoxidizing an oxy-compound of a metal inert to cyanid, the cyanid of which is desired, by the action of an endothermic reducing agent in the presence of carbon and nitrogen and maintaining the ingredients at a reacting temperature by the action of an inert heat absorbing agent.
- 20 31. The process of making cyanids which consists in deoxidizing, in the presence of nitrogen, an oxy-compound of a metal inert to cyanid, the cyanid of which is desired, by the action of a carbid capable of generating heat in the mass during reaction, removing the excess of heat and maintaining the temperature at a reacting point by the action of an inert heat absorbing agent.
32. The process of making potassium cyanid which consists in exposing a composition inert to cyanid containing potassium and oxygen to the action of acetylene and nitrogen and maintaining the temperature at a point at which the hydrogen of the acetylene has an affinity for the oxygen of the oxygen content of the composition in preference to carbon, by the action of an inert heat absorbing agent.
- 40 33. The process of making potassium cyanid which consists in exposing potassium hydroxid to the action of acetylene and nitrogen and regulating and maintaining the temperature of the reacting ingredients at a point at which the hydrogen of the acetylene has an affinity for the oxygen of the potassium hydroxid in preference to carbon, by introducing into the reacting ingredients a heat absorbing agent of inert nature.
34. The process of making alkali-metal cyanid which consists in exposing an oxy-compound of an alkali-metal inert to cyanid, the cyanid of which is desired, to the action of hydrogen carbid and nitrogen and regulating and maintaining the temperature of the reacting ingredients at a point at which the hydrogen content of the hydrogen carbid has an affinity for the oxygen of the oxy-compound in preference to carbon, by the action of an inert heat absorbing agent.
- 50 35. The process of making alkali-metal cyanid which consists in exposing an oxy-compound of an alkali-metal inert to cyanid, the cyanid of which is desired, to the action of acetylene and nitrogen and maintaining the temperature at a point at which the hydro-
- gen content of the acetylene has an affinity for the oxygen of the oxy-compound in preference to carbon, by the action of an inert heat absorbing agent.
- 55 36. The process of making cyanid which consists in uniting the ingredients forming the same while maintaining the temperature below the dissociating point of cyanogen, by refrigeration.
37. The process of making cyanid which consists in uniting nitrogen with carbon and a metal, the cyanid of which is desired, while maintaining the temperature of the uniting ingredients within the sphere of formation and below the dissociating point, by refrigeration.
- 85 38. The process of making cyanid which consists in exposing ingredients capable of forming the same to a reacting temperature and maintaining the temperature within the sphere of formation, by refrigeration.
- 55 39. The process of making cyanids, which consists in fusing an oxy-compound of the metal inert to cyanid, a cyanid of which is desired, and introduced into and through the same an endothermic carbid and nitrogen, while maintaining the materials at a reacting temperature.
- 40 40. The process of making cyanids, which consists in fusing an oxy-compound of an alkali metal inert to cyanid and introducing into and through the same an endothermic carbid and nitrogen, while maintaining the materials at a reacting temperature.
- 100 41. The process of making cyanids, which consists in fusing caustic potash and introducing into and through the same an endothermic carbid and nitrogen, while maintaining the materials at a reacting temperature.
- 105 42. The process of making cyanids, which consists in fusing an oxy-compound of the metal inert to cyanid, a cyanid of which is desired, and introducing into and through the same an endothermic hydrocarbon and nitrogen, while maintaining the materials at a reacting temperature.
- 110 43. The process of making cyanids, which consists in fusing an oxy-compound of an alkali metal inert to cyanid and introducing into and through the same an endothermic hydrocarbon and nitrogen, while maintaining the materials at a reacting temperature.
- 115 44. The process of making cyanids, which consists in fusing an oxy-compound of the metal inert to cyanid, a cyanid of which is desired, and introducing into and through the same acetylene and nitrogen, while maintaining the materials at a reacting temperature.
- 120 45. The process of making cyanids, which consists in fusing an oxy-compound of an alkali metal inert to cyanid, and introducing into and through the same acetylene and nitrogen, while maintaining the materials at a reacting temperature.

46. The process of making potassium cyanid, which consists in fusing caustic potash or substance containing the same and introducing into and through the fused substance acetylene and nitrogen, while maintaining the materials at a reacting temperature.

In testimony whereof I affix my signature in presence of two witnesses.
